UNITED STATES PATENT OFFICE.

CHARLES TANRON, OF SAN FRANCISCO, CALIFORNIA.

WRITING-BOARD FOR THE BLIND.

1,263,147.

Specification of Letters Patent. Patented Apr. 16, 1918.

Application filed November 13, 1917. Serial No. 201,745.

To all whom it may concern:

Be it known that I, CHARLES TANRON, a citizen of France, residing at the city and county of San Francisco and State of California, have invented new and useful Improvements in Writing-Boards for the Blind, of which the following is a specification:

This invention relates to writing boards to be used by the blind, whereby they may 10 be applied to keep a given straight line or series of lines in the course of writing.

One of the objects of the present invention is to provide a simple, cheaply manufactured, easily manipulated board of the 15 character described, which is adapted to receive and secure the paper or material to be written upon and which is provided with a series of parallel, flexible guiding members which permit line after line to be written 20 or properly spaced without moving the paper or the guides provided. Further objects will hereinafter appear.

The invention consists of the parts and the construction and combination of parts 25 as hereinafter more fully described and claimed, having reference to the accompanying drawing, in which—

Figure 1 is a perspective view of the writing board.

Fig. 2 is a cross section of the same.

Referring to the drawings in detail, A indicates a rectangular-shaped frame constructed of wood, metal or any other suitable material. The sides of this frame are 35 grooved or rabbeted, as shown at 2, and they are, furthermore, perforated, as at 3, to permit the frame to be strung, as shown at 4. An ordinary cord may be used and the ends of said cord may be knotted 40 to secure it in place after the frame has been strung, or it may be secured to adjusting screws 5, as shown, to permit the tension of the cord to be varied at will.

The lower side of the frame is recessed, 45 as at 6, for the reception of a panel or board 7. The recess forms a shoulder against which the board rests when inserted, and it is secured in this position first by inserting it in a groove formed at one side or one 50 end of the frame, as shown at 8, and then by swinging latch 9 which locks it in place by entering a groove 10.

The paper or other material to be written upon is placed between the cords 4 and the 55 board. This is accomplished by reversing the frame and removing the panel. The

paper is then placed on the strings within the frame and is here positively secured against movement the moment the panel is placed in position. The frame is then again 60 reversed and is ready for use. The several cords provided run parallel with each other and are equally spaced and thus serve as guides which permit line after line to be written and evenly spaced without moving 65 the paper or the guides provided.

The board is also provided with a marker, such as shown at 11. This marker consists of a pin provided with a glass or other suitable head, to which is attached a cord 13. 70 For instance, if the writer should be interrupted or should desire to temporarily stop, it is only necessary to insert the marker after the last word. The writer may, therefore, return at any time and continue writing by removing the marker, as this indicates the last position or line written upon. 75

While a frame strung as shown and adapted to receive a board has been provided, I wish it understood that the cords or 80 guides may be held in any suitable manner and may be placed directly upon a board, if desired, and that other modifications of a similar nature may be resorted to.

The materials and finish of the several 85 parts of the device may otherwise be such as the experience and judgment of the manufacturer may dictate.

I wish it understood that various changes in form, proportions and minor details of 90 construction may be resorted to within the scope of the appended claims and that I do not wish to limit myself to the specific design and construction here shown.

Having thus described my invention, what 95 I claim and desire to secure by Letters Patent is—

1. A writing board comprising a frame, a plurality of parallel cords secured in said frame, a board adapted to be inserted in the 100 frame to permit the interposition of paper or other material to be written upon between the cords and the board, and means for securing the board and paper in the frame.

2. A writing board for the blind comprising a rectangular shaped frame, said frame being grooved on each side and provided with a series of transverse perforations, a continuous cord adapted to be strung through the perforations in the frame and secured 105 therein to form a series of flexible inter-spaced parallel writing guides, a tensioning 110

2
screw to which one cord end is secured to permit the tension of the cord to be adjusted, a shoulder recess formed on the rear side of the frame, a board adapted to be placed 5 in said recess, a latch adapted to secure the board in the recess, said board forming a support for the material to be written upon, and a marker having a sharp point formed thereon for indicating any desired point in a 10 line of the writing and a cord securing said marker to the frame.

3. A writing board for the blind comprising a frame having a plurality of flexible guiding members secured therein, a board 15 adapted to be secured below the cords to receive material to be written upon, means for securing the board in the frame, a movable marker adapted to be placed at any desirable point along the flexible lines, a pin on the 20 marker to permit the marker to be inserted in the board and a flexible cord securing the marker to the frame.

4. A writing board comprising a frame, a plurality of parallel cords secured in said 25 frame, a board adapted to be inserted in the frame to permit the interposition of paper or other material to be written upon between the cords and the board, means for securing the board and paper in the frame, and means 30 for adjusting the tension of the cords.

5. A writing board for the blind comprising a rectangular-shaped frame, said frame being grooved and perforated along each side, a continuous cord adapted to be strung

through the perforations in the frame and 35 secured therein to form a series of flexible, parallel writing guides, and means for securing and supporting the material to be written upon with relation to the writing guides 40 in the frame.

6. A writing board for the blind comprising a rectangular-shaped frame, said frame being grooved and perforated along each 45 side, a continuous cord adapted to be strung through the perforations in the frame and secured therein to form a series of flexible, parallel writing guides, means for varying the tension of the cord, and a shoulder 50 formed on the lower side of the frame adapted to receive a board, said board being secured to the frame by inserting one side in the groove formed in the frame and by a swinging latch at the opposite end, said board serving as a support for the material 55 to be written upon.

7. An appliance to aid the blind in writing, comprising a support for the paper to be written on, a series of flexible guide cords spaced, writing distance apart, stretched over said support, and a marker for indicating any desired point in a line of the writing.

In testimony whereof I have hereunto set my hand in the presence of two subscribing witnesses.

CHARLES TANRON.
